UNITED STATES PATENT OFFICE.

WALTER W. NEVEGOLD, OF BRISTOL, PENNSYLVANIA.

COUPLING-RETAINER.

SPECIFICATION forming part of Letters Patent No. 270,462, dated January 9, 1883.

Application filed June 13, 1882. (No model.)

To all whom it may concern:

Be it known that I, WALTER W. NEVEGOLD, a citizen of the United States, and a resident of Bristol, Bucks county, Pennsylvania, have invented an Improvement in Coupling-
5 Retainers, of which the following is a specification.

My invention consists of a device, fully described hereinafter, for retaining in place the
10 two couplings by which, and by an intermediate spindle, a roll of one set is connected to
that of another set of rolls in a train, the object of my invention being to obviate the ne-
cessity of resorting to the appliances which
15 are usually employed for this purpose, and
the removal and replacing of which require
tedious manipulation.

In the accompanying drawings, Figure 1 is
20 a front view, partly in section, of part of a roll-
ing-mill train with spindle, couplings, and my
improved retainer; Fig. 2, a transverse section
on the line 1 2, and Fig. 3 a perspective
view of the retainer drawn to an enlarged
25 scale.

25 A represents part of one of the housings of
one set of rolls, and B part of one of the rolls,
which has the usual projection or wabbler b
coupled to a like wabbler, b', on the roll B' of
30 an adjoining set by a spindle, D, and coup-
lings E E'. The projecting ends or wabbles
of the rolls, as well as the spindle D, have the
usual four grooves, e, as shown in Fig. 2, for
receiving the like number of internal ribs in
35 the couplings. As these couplings are always
loose on the intermediate spindle and on the
wabbles of the rolls, they are apt to creep
away from the latter on the spindle, and to
40 prevent this it has been the common practice
to wrap leather straps, hoop-iron, or thick wire
on the spindle between the two couplings, and
this must be unwrapped and removed when
45 the rolls of the two sets have to be uncoupled.
In order to obviate the necessity of resorting
to these retaining-wrappings, I use a bar, G,
long enough to pass freely between the two
50 couplings E E', and secure to this bar two
curved springs, h h', each of which is bent

50 abruptly at x, so that it will engage into one
of the grooves of the intermediate spindle D.
These springs are preferably made of one elas-
tic bar or plate, H, secured midway between
its opposite ends to the center of the bar G, as
55 shown in Fig. 3.

Instead of the two springs h h', a curved
rigid arm may take the place of one of the
springs; but I prefer the two springs. The
two springs will retain the bar G in its place,
60 and it will effectually prevent the creeping
away of the couplings from the wabbles of
the rolls.

65 Prior to uncoupling the rolls the retainer
may be instantly detached by applying such
force to one of the springs that its bend x
shall be dislodged from the groove in the
spindle.

65 An important advantage of my invention is
the prevention of the rattling noise which ac-
companies the use of the ordinary retaining-
wrappings.

70 I claim as my invention—
1. The within-described coupling retainer,
the same consisting of the bar G, adapted to
fit freely between the couplings, and having
75 bent arms h h', one or both being elastic, and
one of which is adapted to engage into one
groove and the other into another groove of
the coupling-spindle, all substantially as set
forth.

2. The combination, with the coupling-spindle D and couplings E E', of the retaining-bar G and its springs h h', constructed to engage
80 into grooves of the said spindle D, substan-
tially as set forth.

3. The coupling device in which a bar, G,
is combined with a bent elastic bar, H, form-
ing two springs, h h', substantially as speci-
fied.

85 In testimony whereof I have signed my name
to this specification in the presence of two sub-
scribing witnesses.

WALTER W. NEVEGOLD.
